UNITED STATES PATENT OFFICE.

JOSEPH H. POPE, OF HAMILTON, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

BLANK-FEEDING MECHANISM FOR SKIVING-MACHINES.

1,305,236.

Specification of Letters Patent. Patented May 27, 1919.

Application filed August 20, 1915. Serial No. 46,467.

To all whom it may concern:

Be it known that I, JOSEPH H. POPE, a citizen of the United States, residing at Hamilton, in the county of Essex and State 5 of Massachusetts, have invented certain new and useful Improvements in Blank-Feeding Mechanism for Skiving-Machines; and I do hereby declare the following to be a full, clear, and exact description of the invention, 10 such as will enable others skilled in the art to which it appertains to make and use the same.

The present invention relates to feeding mechanism and more particularly to mechanism for separating and feeding box toe or counter blanks in a skiving machine.

In a well-known type of machine for skiving the edges of box toes and counters, the blanks are fed one at a time from the bottom of a pile or stack to the die and pressure rolls immediately behind which is located the fixed skiving knife. The blanks which are cut from leather or other suitable material are often warped or bent so 25 that pressure is usually applied to the pile to hold the blanks in proper flattened condition for feeding. Where any considerable pressure is required or where, owing to the material of which the blanks are composed, 30 there is considerable frictional resistance offered to the separation or sliding of the lowermost blank from beneath the pile, difficulty is experienced in properly feeding the blanks. This difficulty is further increased with that type of blank having a 35 beveled edge, the feeding member tending to pass either under or over the lowermost blank instead of properly advancing it to the feed rolls.

40 One of the objects of the present invention is to provide mechanism which shall positively and accurately feed blanks or similar articles one at a time from a pile or stack. Another object is to provide mechanism for feeding the lowermost blank or similar article from a pile held under pressure. Another object is to devise mechanism for feeding blanks or similar articles having a thin or beveled edge. Still another 45 object is to provide mechanism which is particularly adapted and suitable for feeding the various kinds of box toe and counter

blanks in a skiving machine of the type above referred to.

With these objects in view, the present 55 invention consists of the devices and combinations of devices hereinafter described and more particularly defined in the claims.

In the accompanying drawings, which illustrate what is now considered to be the 60 preferred embodiment of the present invention, Figure 1 is a view in side elevation of a leather skiving machine embodying the present invention, and Fig. 2 is a longitudinal sectional view of the upper portion of the machine. Fig. 3 is a plan view of the machine with parts of the magazine and table removed; Fig. 4 is a vertical sectional view of the blank feeding mechanism taken on the line 4-4 of Fig. 3; Fig. 5 is a detailed front view in elevation, showing the blank feeding mechanism; Figs. 6, 7, and 8 are vertical sectional views taken through the magazine or hopper for the blanks, illustrating the position of the separating blade 65 and the feed plate in different steps of the feeding operation; Fig. 9 is a plan view, and Fig. 10 an edge view of a sheet of leather or leather board illustrating the 70 method of cutting the blanks from the stock. 75

The machine illustrated in the drawings is similar in construction, arrangement, and mode of operation of many of its parts to the machine disclosed in the patent to Scott No. 969,987, dated September 13, 1910, to 80 which reference may be had for a more detailed description of such parts.

The machine is provided with a positively driven die roll 20, a pressure roll 22, and a skiving knife 24 the cutting edge of which extends close to the bite of the die and pressure rolls which act as feed rolls for carrying the blank against the skiving knife.

The blanks, which may be for counters or box toes, are placed in a pile in the hopper or magazine formed by the front wall 26 and side gages 28, the lower part of the front wall 26 being provided with a vertically movable gate 30. The counter or box toe blanks are formed of comparatively thin leather or other material and are often so warped or bent, that in order to hold them in a flat position upon the bedplate 32, a follower 34 is placed on top of the pile and

is forced down by the pressure rod 36, actuated by means of a rack and pinion from a shaft 38 driven by a friction clutch. The parts thus far described are substantially 5 the same in their construction and mode of operation as in the patented machine above referred to.

The devices for separating and feeding one blank at a time to the feed rolls comprise 10 a separator blade 42, a gate lifter 44, and a feed plate 46. The separator blade is arranged to pass between the two lowermost blanks, after which it is raised slightly with the gate by means of the gate lifter to free 15 the bottom blank and to permit it to be advanced by the feed plate from beneath the pile of blanks and under the gate to the feed rolls. These separating and feeding devices are all carried and actuated by the 20 feed slide 47, which is arranged to reciprocate in guideways 48 formed in the bed plate 32 of the machine. The top of the feed slide 47 is channeled as at 49 to receive the carrier 50 for the gate lifter 44 and the feed 25 plate 46. The adjusting screw 51 and clamping screws 52 provide a convenient means for adjusting the carrier and feed plate toward or from the feed rolls, so that the feed plate will present the blank to the 30 feed rolls in proper timed relation.

The feed plate 46, which slides back and forth upon the bed plate of the machine, is rigidly secured to the front end of the carrier 50 by means of the screws 53. On top 35 of the carrier, and near its front or advancing end are formed a transverse slot 55 and the longitudinal slot 56. In the transverse slot 55, which is slightly below the longitudinal slot 56, is secured the yoke-shaped 40 gate lifter 44, the forward or advancing ends of the arms 57 of which are beveled as at 58, and arranged to engage the anti-friction rolls 59 carried by the gate 30, the forward movement of the lifter first raising and then 45 holding raised the gate against the action of gravity and the springs 60 to permit the passage thereunder of the blank to the feed rolls.

The separator blade 42, which is arranged 50 to slide upon the top of the feed plate 46, is rigidly secured to the front end of the separator slide 61 mounted to slide in the longitudinal groove 56 in the top of the carrier 50, being held therein by the cover 55 62 and screws 53 and 63, the former of which also serves to secure the feed plate 46 to the feed slide 47.

The front or advancing edge of the separator blade 42 is preferably beveled as 60 shown, so as to more readily enter between the two lowest blanks of the pile. The separator blade 42 is actuated by the feed slide through the following connections: Secured to the rear end of the separator slide 61 is 65 the rack bar 64, (see Figs. 3 and 5), which

by means of the differential gear 68 is geared to the rack 66 fixed on the bed plate 32. The rack 64 is provided with the guide 69 arranged to slide in the guideway 70 formed by the upwardly projecting flange 71 on the feed slide and a guide bar 72 secured to the bed plate 32. The differential gear 68 is mounted upon an outwardly projecting flange 74 of the feed slide 47 and has a long radius sector 76 in engagement with the rack 75 bar 64, and a short radius sector 78 in engagement with the rack 66.

The above-described arrangement is such that when the feed slide begins its advancing or feeding stroke, the separator blade 80 will also be advanced, but at a much faster rate owing to the differential action of the gear 68 which is then turning in anti-clockwise direction. The separator blade thus makes its complete forward or separating 85 stroke during the first portion of the forward movement of the feed slide, and stops with the teeth or projections 90 on its front edge in the recesses 92 in the gate near its bottom edge. By this time the short radius 90 sector 78 of the differential gear has moved out of mesh with the two teeth on the fixed rack 66, so that during the continued advancing or feeding movement of the feed 95 slide the separator blade may remain stationary, the gear 68 then turning freely in the opposite or clockwise direction.

In order to maintain the separator blade in its advanced position during the first portion of the return stroke of the feed slide 100 and to insure the proper re-meshing of the short radius sector 78 with the fixed rack 66, a tension spring 80 has been provided, one end of which is secured to the cover 62 carried by the feed slide, while the other end 105 is attached to the rack 64 carried by the separator slide. This spring, it will be noted, will hold the separator blade in its advanced position until the return movement of the feed slide has brought the short radius 110 sector 78 into engagement with the fixed rack 66, after which the final portion of the rearward movement of the feed slide will impart a quick return movement to the separator blade.

The feed slide is reciprocated by mechanism substantially like that shown in the Scott patent above referred to, such mechanism comprising a link 82, rock arm 84 and shaft 86, and actuating cam of the gear 88. 115 120

In order to facilitate the feeding of the lowermost blank by the feed plate, the pressure exerted upon the blank is preferably relieved in whole or in part, this being accomplished by slightly raising the separator 125 blade after it has been inserted between the lowermost blank and the one next above. The blade is raised by the gate 30, the bottom of the recesses or slots 92 in the gate engaging the under side of the projections 130

90 on the forward edge of the blade and springing the blade upwardly when the gate is lifted by the beveled faces 58 on the arms 57 of the gate lifter 44. The timing of the 5 parts is such that the gate and separator blade will be lifted before the feeding of the lowermost blank begins.

The machine is provided with the usual 10 guard or table 104 which covers the feeding mechanism and which acts as a gage to hold the bottom blanks against the gate 30, also preventing the lowermost blank from being drawn backwardly from beneath the pile by the separator blade during its rearward or 15 return stroke.

While the feeding mechanism illustrated herein is well adapted for feeding all types of flat blanks, it is particularly well adapted for feeding blanks having a beveled edge 20 such as are illustrated in Figs. 9 and 10. These blanks 110 are cut from a sheet of material whose width is substantially the length of the counter to be made, the individual blanks being cut by a knife which 25 swings in an arc to give a curvature approximately the curvature of one side of the finished blank. By mounting the knife so that it is inclined laterally, a beveled edge is imparted to the blank, thus saving the 30 width of the bevel or scarf in stock for each blank cut.

This feather or beveled edge renders the feeding of the blanks quite difficult, especially if the blanks are under considerable 35 pressure or the bottom blank sticks to the blank above. With the feeding mechanism described above, however, the beveled teeth 90 of the separator blade readily enter between the beveled edges of adjacent blanks 40 and separates the bottom blank from the pile. Furthermore, when the blade is in position between the pile and the bottom blank, as illustrated in Figs. 7 and 8, the bottom blank 45 is inclosed in a metallic tube or guideway, so that there is little resistance to its movement to the feed rolls; and at the same time the feed plate is prevented from sliding up the beveled edge of the blank.

The operation of the machine is as follows:

50 A pile of blanks is placed upon the bed-plate 32 between the side gages 28 and against the front plate 26 and gate 30. The side gages are adjusted to hold the blanks in proper relation to the cavity of the die 55 roll, and then the follower 34 and pressure rod 36 are brought down to hold the pile in a flat position under pressure. The feed rolls are set in operation and the feeding mechanism operates in timed relation to the 60 feed rolls. The relative positions of the separator blade, gate lifter and feed plate at the beginning of the feed stroke is shown in Fig. 3. In the first part of the feeding stroke of the feed slide 47, the differential 65 gear 68, aided by the spring 80 pushes the

separator blade from the position shown in Fig. 6 to the position shown in Figs. 2 and 7. When the separator blade has reached 70 the gate 30, the rack bar 64 engages a stop 114 on the slide bar 72 and holds the separator slide from further movement. The arms 57 of the lifter yoke 44 then pass under the friction rollers 59 to lift the gate and separator blade with the pile of blanks on the blade. A continued movement of the 75 feed slide brings the feed plate into contact with the bottom blank to advance it under the gate to the feed rolls, as shown in Fig. 8. Upon the return stroke of the feed slide, the separator blade is held stationary by the 80 spring 80 until the short radius sector 78 is brought into engagement with the rack 66, when the separator slide will be given a quick return stroke, the parts coming to rest 85 in the position shown in Fig. 3.

While the apparatus illustrated herein is well adapted for feeding counters with a beveled edge, it is to be understood that the invention is not necessarily limited to a machine for feeding such counters, but may be 90 employed for feeding other forms of counters or box toes. Furthermore, some of the features of the present invention may be embodied in machines other than skiving machines and for feeding other kinds of blanks 95 or other articles.

The terms "in front of" and "in advance" are used in the specification and claims to indicate the direction of feed of the blanks. Where reference is made to a 100 pile or stack this is to be understood as referring as well to horizontal piles or stacks as to vertical, and whenever the bottom blank or bottom of the pile is specified, this is to be taken as meaning also the end blank 105 or end of a horizontal pile or stack.

Having thus illustrated and described the preferred form of the invention, what is claimed as new is:—

1. Blank feeding mechanism for skiving 110 machines comprising a fixed support, a magazine for holding blanks in a pile upon the support, mechanism for feeding the bottom blank of the pile to the skiving devices, and devices for holding the pile of blanks up 115 off the bottom blank while it is being fed.

2. Blank feeding mechanism for skiving 120 machines comprising a support for blanks, a magazine for holding blanks in stacked formation on the support, a separator movable through the stack into position above the bottom blank to confine the bottom blank between the separator and the support, and a feeding device movable between the support and the separator to advance 125 the blank to the skiving devices.

3. Blank feeding mechanism for skiving 130 machines comprising means for supporting the blanks in a pile, means for positively pressing the pile against the support, a sepa-

- 5 rator plate arranged to separate the bottom blank from the rest of the pile and to relieve the pressure on the bottom blank, and mechanism for feeding the bottom blank to the skiving devices.
4. Blank feeding mechanism for skiving machines comprising means for supporting the blanks in a pile under pressure, a separator to enter between the two bottom blanks, means to raise the separator and the pile of blanks to relieve the pressure on the bottom blank, and a feeding device for feeding the bottom blank to the skiving devices.
5. Blank feeding mechanism for skiving machines comprising means for supporting the blanks in a pile, means for pressing the blanks against the support, a separator having a beveled edge to enter between the two bottom blanks to free the bottom blank upon the support, and a feeding device for advancing the bottom blank out from under the separator to the skiving devices.
6. Blank feeding mechanism for skiving machines comprising a magazine for holding a plurality of blanks in a pile, a gate in the front of the magazine, a separator for entering between the bottom blank and the pile, means for feeding the bottom blank, and devices for lifting the gate to permit feeding.
7. Blank feeding mechanism for skiving machines, comprising means for supporting the blanks in a pile, a feed slide having a reciprocatory movement, a separator mounted on the feed slide, and means for operating the feed slide and separator arranged to accelerate the movement of the separator at the beginning of the feeding stroke of the feed slide to separate the bottom blank from the pile and then to cause the feed slide to feed the separated blank.
8. Blank feeding mechanism for skiving machines, comprising means for supporting the blanks in a pile, a reciprocatory feed slide, a separator mounted on the slide, means to actuate the slide, and means to accelerate the separator relatively to the feed slide on the forward and return strokes of the slide.
- 50 9. Blank feeding mechanism for skiving machines, comprising means for supporting the blanks in a pile, a separator to enter between the bottom blank and the pile, means to raise the separator and pile to free the bottom blank, and a feeding device to feed the separated blank from under the pile.
- 55 10. Feeding mechanism for skiving machines comprising a magazine for holding a plurality of blanks in a pile, a gate in the front of the magazine, means for feeding the blanks, and means for raising the gate to permit a blank to pass.
- 60 11. Blank feeding mechanism for skiving machines, comprising means for supporting the blanks in a pile, a gate in front of the

pile, a separator for entering between the two bottom blanks and engaging the gate, a feed member for advancing the bottom blank, and means operated in timed relation to the feed movement to raise the separator 70 and gate.

12. Blank feeding mechanism for skiving machines comprising a magazine for supporting blanks in a pile, a gate at the bottom of the magazine, a feed slide carrying a separator, a gate lifter, and a feeding member, and means for actuating the feed slide to cause the separator to separate the bottom blank from the pile, the gate lifter to raise the gate and the feeding member to 80 advance the bottom blank under the gate.

13. Blank feeding mechanism for skiving machines comprising a machine frame, a feed slide, a separator movably mounted on the slide, a rack on the frame, a rack on the 85 separator, differential gearing between the racks, and means for moving the slide.

14. Blank feeding mechanism for skiving machines comprising a machine frame, a feed slide, a separator movably mounted on 90 the slide, a rack on the frame, a rack on the separator, differential gearing between the racks arranged to be thrown into and out of engagement with one of said racks, a spring connection between the separator and 95 the slide, and means for moving the slide.

15. Blank feeding mechanism for skiving machines comprising a machine frame, a feed slide, a separator movably mounted on the slide, gearing mounted between the 100 frame and separator, and a spring connecting the slide with the separator.

16. Blank feeding mechanism for skiving machines comprising a machine frame, a feed slide, a separator movably mounted on 105 the slide, accelerating devices on the slide mounted between the frame and separator, a stop on the frame, and a spring connecting the separator with the slide.

17. Blank feeding mechanism for skiving machines comprising a magazine for holding blanks, a gate in front of the magazine, a feeding member, and means connected with said member and located in advance thereof to raise the gate to permit the feed 110 member to feed blanks under the gate.

18. Blank feeding mechanism for skiving machines comprising a machine frame, a feed slide on the frame, a feed member connected to the slide, a separator movably mounted on the slide, means for actuating the slide to operate the feed member and separator, an accelerator to rapidly advance the separator to the end of its forward path, and a stop to hold the separator while the 125 feed member completes its feeding movement.

19. Blank feeding mechanism for skiving machines comprising a magazine for supporting the blanks in a pile, a vertically 130

- movable gate at the bottom of the magazine, a feed slide and means for actuating the same, and devices connected with the feed slide for raising the gate to permit the feeding of a blank to the skiving mechanism.
20. Blank feeding mechanism for skiving machines comprising a magazine for supporting the blanks in a pile, a vertically movable gate at the bottom of the magazine, a feed slide, and a yoke-shaped gate lifter carried by the feed slide having its arms of such a length and beveled at their free ends to raise the gate and hold it raised for the feeding of a blank.
21. Blank feeding mechanism for skiving machines comprising a machine frame, a feed slide, a separator movably mounted on the slide, and means controlled by the feed slide for imparting a rapid advancing movement to the separator during the first portion of the advancing stroke of the feed slide and holding the separator stationary during the latter portion of the advancing stroke of the feed slide.
22. Blank feeding mechanism for skiving machines comprising a machine frame, a feed slide, a separator movably mounted on the slide, a stop on the frame, a spring normally tending to advance the separator, and accelerating devices for controlling the advancing movement of the separator from the feed slide.
23. Blank feeding mechanism for skiving machines comprising means for supporting the blanks in a pile, a reciprocatory feed slide, a separator mounted on the slide and actuated thereby, and means for actuating the slide.
24. Blank feeding mechanism for skiving machines comprising a support for blanks, a mechanism for holding blanks in stacked formation upon the support, a separator movable through the stack into a position above the bottom blank to confine the bottom blank between the separator and the support, and a feed slide arranged to move between the separator and the support to push the blank out to the skiving devices.
25. Blank feeding mechanism for skiving machines comprising a fixed support for supporting the blanks in a pile, a separator having a beveled edge to enter between the two bottom blanks to free the bottom blank upon the support, a reciprocatory feed slide, and means for actuating the separator and slide.
26. Blank feeding mechanism for skiving machines comprising means for supporting the blanks in a pile, a separator to enter between adjacent blanks in the pile, a reciprocatory feed slide to feed a blank between the separator and support, and means for actuating the separator and the slide with their idle strokes in the same direction and overlapping.

JOSEPH H. POPE.
